UNITED STATES PATENT OFFICE

OLIVER J. PHELPS AND DAVID F. EASTBURN, OF SALEM, OREGON

SPICE CAN RACK

Application filed December 16, 1929. Serial No. 414,378.

The invention aims to provide an exceptionally simple and inexpensive, yet a very desirable rack for holding a plurality of spice cans or other articles, the construction being such that one row of cans is normally 5 accessibly exposed and a second row may be similarly exposed by inverting the can-supporting portion of the rack.

With the foregoing in view, the invention resides in the novel subject matter hereinafter described and claimed, the description being accomplished by reference to the accompanying drawings.

Fig. 1 is a perspective view.

Fig. 2 is a vertical transverse section.

Fig. 3 is an enlarged detail vertical section cut longitudinally through one end portion of the device.

The drawings above briefly described illustrate the preferred form of construction and while this construction will be herein specifically explained, it is to be understood that within the scope of the invention as claimed, variations may be made.

The numeral 5 denotes two vertical end walls whose shape is somewhat that of a parallelogram, although the longitudinal edges of these walls may be curved as shown, instead of straight. A bottom 6 and a top 30 6' extend between the end walls 5 and are secured thereto, the front longitudinal edge 35 of the bottom 6 being provided with a vertical flange 7, while the rear longitudinal edge of the top 6' is provided with a similar flange 7'. Secured to and projecting rearwardly from the rear edge of the bottom 6, are a number of spring fingers 8 preferably formed from wire, and a plurality of similar fingers 8' project forwardly from 40 the upper longitudinal edge of the top 6'.

A longitudinal shaft 9 passes centrally through and is secured to the end walls 5, provision is made for rotatably mounting this shaft, a knob 10 is provided for rotating it, and means such as a spring-pressed detent 11, is provided for normally holding the shaft and rack against rotation.

In the present showing, two vertical end walls 12 are disposed at the outer sides of 50 the end walls 5 and are provided with bear-

ing openings 13 in which the ends of the shaft 9 are rotatably received, the inner side of one of said walls 12 being provided with two shallow sockets 14 and 14', in either of which the spring-pressed detent 11 is receivable, said detent being carried by one of the end walls 5. The walls 12 project above the rotatably mounted rack and support a shelf 15 and a back 16, which shelf and back 55 secure said walls in fixed relation with each other.

In using the device, it may either rest upon a shelf, table or other support, or may be hung upon the wall. The cans C of 60 spices, or other articles to be held by the rack, are inserted behind the flanges 7 and 7' and engaged with the spring fingers 8 and 8', the shaft 9 serving to limit the amount of insertion. The spring detent 11 65 when engaged with the socket 14, holds the rotatable rack in such position that one row of the cans C is exposed accessibly, and by simply inverting the rack by means of the knob 10 so that detent 11 snaps into the socket 14', the other row of cans is placed 70 in position for quick and easy withdrawal. Hence, the device may be easily and advantageously used for holding quite a number of cans and allowing any one to be removed and reinserted with ease, whenever 75 necessary.

As above stated, the details disclosed are 80 preferably followed, but within the scope of the invention as claimed, variations may be made.

We claim:—

1. A rack of the class described comprising end walls, a top and a bottom extending between and secured to said end walls, a central longitudinal divider disposed between said top and said bottom and extending between said end walls to limit inward movement of articles into the space between said bottom and top, releasable means for holding the articles against the upper side 90 of said bottom and against the lower side of said top, means rotatably supporting said end walls to allow complete inversion of the rack, and releasable means for normally holding the rack against rotation. 95

2. A rack of the class described comprising end walls, a top and a bottom extending between and secured to said end walls, a longitudinal shaft between said top and said bottom, said shaft passing centrally through said end walls and acting as means for limiting insertion of articles into the space between said bottom and top, means supporting said shaft to rotatably mount the rack and allow complete inversion of the rack, releasable means for holding the articles against the upper side of said bottom and against the lower side of said top, and releasable means for normally holding the rack against rotation.
3. A rack of the class described comprising two end walls, a top and a bottom extending between and secured to said end walls, the front longitudinal edge of said bottom and the rear longitudinal edge of said top being provided with a vertical can-retaining flange, a plurality of can-engaging spring fingers projecting forwardly from the front edge of said top, a plurality of can-engaging spring fingers projecting rearwardly from the rear edge of said bottom, means rotatably supporting said end walls to allow complete inversion of the rack, and releasable means for normally holding the rack against rotation.
4. A rack of the class described comprising two end walls, a top and a bottom extending between and secured to said end walls, the front longitudinal edge of said bottom and the rear longitudinal edge of said top being provided with a vertical can-retaining flange, a plurality of can-engaging spring fingers projecting forwardly from the front edge of said top, a plurality of can-engaging spring fingers projecting rearwardly from the rear edge of said bottom, a shaft passing longitudinally through the centers of said end walls and serving as means for limiting the insertion of cans into the rack, means supporting said shaft to rotatably mount the rack and allow complete inversion thereof, and releasable means for normally holding the rack against rotation.
5. In testimony whereof we have hereunto affixed our signatures.

OLIVER J. PHELPS.
DAVID F. EASTBURN.
